US00D905519S

(12) **United States Design Patent** (10) Patent No.: **US D905,519 S**
(45) Date of Patent: **** Dec. 22, 2020**

(54) **HOT AIR BLOWING TOOL FOR MELTING SOLDER**

(71) Applicant: **Guangzhou Yihua Electronic Equipment Co., Ltd.**, Guangdong (CN)

(72) Inventor: **Mingkang Gou**, Guangdong (CN)

(73) Assignee: **Guangzhou Yihua Electronic Equipment Co., Ltd.**, Guangdong (CN)

(**) Term: **15 Years**

(21) Appl. No.: **29/691,137**

(22) Filed: **May 14, 2019**

(51) LOC (12) Cl. **08-05**

(52) U.S. Cl.

USPC **D8/29.1**

(58) **Field of Classification Search**

USPC D8/29.1, 29.2, 30, 69, 107; D28/133;

D15/144

CPC F24H 3/00; F24H 3/02; F24H 3/0423

(57) **CLAIM**

The ornamental design for a hot air blowing tool for melting solder, as shown and described.

DESCRIPTION

FIG. 1 is a perspective view of the hot air blowing tool;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in figures are to show unclaimed subject matter and form no part of the claimed design.

1 Claim, 4 Drawing Sheets

FIG. 3

FIG. 2

FIG. 4

FIG. 5

FIG. 6

FIG. 7
